ELECTROLYTIC DEVICE AND METHOD
OF MAKING SAME

Joseph B. Brennan, Bratenahl, Ohio

Application July 18, 1942, Serial No. 451,407

2 Claims. (Cl. 175—315)

This invention relates to electrolytic devices and more particularly to containers for electrolytic devices. The invention is described herein as applied to electrolytic condensers, but those skilled in the art will appreciate that the invention is useful in conjunction with other devices and other types of electrolytic devices such as, for example, lightning arresters, rectifiers and the like. This application is a continuation in part of my copending application Serial No. 289,607, filed August 11, 1939, now Patent No. 2,290,163 issued July 21, 1942.

One of the objects of my invention is to provide electrolytic devices which will be durable and leak proof in service, and which can be manufactured and assembled at low cost. A further object is to provide a simple vent and seal construction adapted especially for electrolytic devices, although it is also useful in other environments. Another object is to provide a method of making such a seal. Another object is to provide a method of forming and aging condensers and the like. Another object is to provide electrolytic devices so constructed and arranged that the formation or aging operations can be carried out or completed after partial or complete assembly of the component parts of the device. Further objects and advantages of my invention will become apparent from the following description of a preferred form thereof reference being made to the accompanying drawing wherein:

Figure 1 is a perspective view of a condenser made according to my invention.

Figure 2 is a view illustrating the component parts of the condenser shown in Figure 1 before the assembly has been completed.

Figure 3 is a somewhat diagrammatic illustration showing my aging or forming method as applied to a condenser of the type shown in Figure 1, but embodying a vent not shown in Figure 2.

Figure 4 is a side elevation partially in section showing the condenser of Figure 3 after the forming or aging operation has been completed and the condenser sealed.

It has heretofore been the practice to enclose electrolytic condensers of the paste type in containers of a cardboard which must be tarred or waxed to prevent leakage and which in spite of all precautions frequently are found to be defective. Another type of container ordinarily used in conjunction with condensers of the wet type consists of a fairly heavy gauge aluminum can having a depending neck portion through

which the anode terminal extends. These containers are generally satisfactory but are expensive to produce and require closures at both the top and bottom thereof.

According to my invention I eliminate the difficulties noted above and produce a low cost yet leakproof and durable container by employing a seal or closure construction which enables me to utilize a light gauge tube of aluminum or other ductile metal, or a tube composed of paper or various plastic materials. Preferably one end of the tube is closed and the other end is open for substantially the full diameter of the tube, although a tube open at both ends may be employed. To close the open end, or ends, I preferably employ a plug composed of resilient rubber (the term "rubber" as used throughout the specification and claims is intended to include not only natural rubbers and rubber-like materials, but also various synthetic rubbers and rubber-like materials) through which the condenser terminals extend. The light gauge tube may not have sufficient strength of itself to engage the plug with sufficient force to create the necessary type of seal. To obviate this difficulty, I employ a seal which is useful and advantageous in other environments, and in which the rubber is compressed into leak proof engagement with the aluminum tube by deforming the tube inwardly and clamping it into deformed position by a clamping device such as a band or wire composed of a heavier or stronger material. The construction embodying the resilient rubber plug also makes possible the use of a simple and effective vent, and permits the circulation of electrolyte within the container during the final forming or aging operations, as will be described more fully below.

A preferred form of my invention is illustrated in the drawing wherein the container, which may be light gauge, extruded aluminum tube having a wall thickness of about 0.005 inch for example, is indicated at 10. In the specification and claims the terms "light gauge" and "thin walled" are used with respect to the tube or container to define a material of such thinness that it does not of itself possess sufficient strength or rigidity to engage the resilient sealing member or plug with sufficient force to create the type of seal required by the service for which the device is intended. The open end of the container is closed by a plug 11 of resilient rubber through which pass the terminals 12 and 14 of the electrode assembly indicated generally at 15. The electrode assembly forms no part of the

present invention as any ordinary type of electrode may be utilized in conjunction with my container. The assembly illustrated at 14 may comprise, for example, two electrodes of film forming material rolled up together with suitable spacers to prevent contact between the electrodes, the whole being impregnated with a film maintaining electrolyte which is retained within the container 10.

As shown particularly in Figure 2 the component parts of a condenser embodying my invention may be assembled by merely inserting the electrode assembly 15 with the container 10, pushing the closure member 11 into the open end of the container, and slipping the ring 16 over the end of the container in the region adjacent the plug 11. Preferably the terminals 12 and 14 are passed through slits cut in the plug 11 before the parts are positioned in their assembled relationship. It is sometimes desirable to employ separately formed terminals 12 and 14 and weld or otherwise join them to electrode tabs or terminals 17 and 18 as indicated at 19 and 20 rather than to extend the terminals 12 and 14 into the electrode assembly. If such a construction is employed as shown in the drawing then it is preferable to position the joints 19 and 20 within the resilient rubber plug 11, the result being that when the plug is compressed onto the terminals the joint is effectively sealed and protected against corrosion.

After positioning the parts as described above the ring 16, which may be composed of steel or other relatively strong metal, or may be of the same material as the tube, i. e., aluminum in the present case, only of heavier gauge, is deformed inwardly. This operation may be performed by spinning or rolling the ring into the arcuate shape shown in Figures 1 and 3 thus deforming the soft ductile metal of the container 10 into intimate sealing engagement with the plug, retaining the container in sealing engagement with the plug, and compressing the plug. By reason of the compression of the material of the plug, an effective seal is made between the electrode terminals 12 and 14 and the plug, thus preventing any possible leakage of electrolyte at these points. As illustrated in the drawing the ring 16 may be provided with means for mounting the device in a support such as, for example, the perforated ears 22 which extend radially outwardly from the ring.

In subjecting electrolytic condensers to their final film forming and aging process it is frequently desirable to circulate the electrolyte around and through the electrodes. This insures proper penetration of the electrolyte throughout the electrode assembly, and assists in dislodging gas bubbles, thereby reducing leakage and preventing defects from occurring in condensers when they are put in service. Also the temperature of the electrolyte may be maintained with the desired range aiding in the production of a film of the desired character. In addition, for some purposes, it is desirable to employ a different electrolyte for the forming or aging operation than is employed when the condenser is in service. Heretofore, a different electrolyte could not be employed with the usual compact type of condenser except by carrying out the forming and aging operations before the condenser was finally assembled. This necessitated handling of the formed or partly formed electrode and the handling frequently resulted in increased leakage in the condenser. According to my pres-

ent invention the forming and aging operations can be carried out with the electrodes assembled within the container, yet it is possible to circulate the electrolyte during these operations or to use one electrolyte for the forming and aging and then to supply a different electrolyte for service if desired.

These operations may be accomplished very conveniently in the manner illustrated in Figure 3. As there shown the electrodes 15, terminals 12 and 14, plug 11 and ring 16 may all be assembled with the container 10. Preferably, but not necessarily, prior to deforming the ring into clamping engagement with the container, small openings as at 29 and 30 are pierced through the plug 11, preferably without removing any material therefrom, and small tubes or needles 31 and 32 inserted through the openings into communication with the interior of the container 10. Electrolyte may then be pumped into the container through the tube 31, for example, while the electrolyte flows out through the tube 32.

The terminals 12 and 14 may be connected to a suitable source of electromotive force as by the conductors 33 and 34 and in this manner the condenser or other electrolytic device may be subjected to the desired film forming and aging operations while electrolyte is being circulated through the condenser by means of the tubes 31 and 32 projecting through the plug 11. Obviously the temperature of the circulating electrolyte can be controlled by suitable means such as coils, for example, disposed externally of the condenser. Thus the electrolyte can be either heated or cooled to the desired temperature. If it is desired to use one electrolyte for forming or aging and another electrolyte in service, the forming electrolyte may be evacuated by means of gas pressure or vacuum, the condenser being inverted; or the service electrolyte may be circulated after the forming or aging operation is completed, and this circulation may be continued until substantially all of the forming or aging electrolyte is removed from the condenser.

In order to provide a vent, if one is required, a small tube 35 may be inserted through the rubber plug 11 as illustrated in Figures 3 and 4. The opening for the tube preferably is merely pierced without removing any material of the plug, and the tube may either be provided with a fusible wax core or may be of such small diameter that it will substantially prevent the escape of liquid from the interior of the condenser while permitting the escape of gas. The compression of the plug by the ring 16 will effectively seal the plug against the exterior of the vent tube 35. A vent is not essential for some types of condensers, and no vent is illustrated in Figures 1 and 2. Otherwise, the condenser shown in Figures 3 and 4 is identical with that shown in Figures 1 and 2.

After the aging process has been completed the condenser may be made ready for shipment and sale merely by removing the tubes 31 and 32 and then compressing the ring 16 inwardly to deform the container 10 into intimate engagement with the plug 11 and to compress the plug. Obviously, if the ring was compressed prior to forming the film, no further deformation will be necessary as the compressive stresses in the rubber will result in the immediate sealing of the openings as soon as the tubes are removed. The compression of the plug results in completely closing and effectively sealing the openings 29 and 30 through which the tubes 31 and 32 were inserted. The

compression of the plug is preferably such that after the tubes 31 and 32 are removed, the openings are almost invisible, the closed openings being indicated diagrammatically by dots and lines, respectively, in Figures 1 and 4. By this method, and with this construction the electrolyte can be circulated around the electrodes during the aging process which can be carried out with the condenser in its finally assembled form; and after the aging process has been completed the condenser can be sealed up without requiring any handling of the electrodes thus eliminating any possibility of contamination of the condenser.

From the foregoing it will be evident that I have provided a simple and economical construction for devices such as electrolytic condensers whereby light gauge tubes can be utilized as containers. By my invention an effective seal can be produced between a light gauge tubular member and a resilient member disposed therewithin, and the resilient member can be compressed and sealed against members such as terminals, vents, and the like passing through it. My construction lends itself to easy and economical assembly methods and condensers made according to my invention can be formed or aged with circulating electrolyte, with the electrodes in their final assembled relationship and without requiring any additional handling of the electrodes, thus obviating the possibility of any subsequent contamination of the electrolyte or electrodes, or damage to the electrodes. The temperature of the electrolyte may be controlled during formation or aging and different electrolytes may be employed, all without requiring any subsequent handling or disturbance of the electrodes. Thus the final forming or aging operation (sometimes called "healing" or "curing") can be carried out under most advantageous conditions to produce a condenser having low leakage losses, and the condenser is completed without disturbance to the electrodes thereafter.

In the foregoing specification I have described preferred forms of my invention merely by way of example and with no intention that my patent should be limited to the precise embodiments disclosed herein. Various modifications and changes can be made in the constructions and methods

shown and described herein, and the invention can be adapted to other devices without departing from the spirit and scope of my invention. Therefore it is to be understood that my patent is not limited to the forms illustrated and described herein or in any manner other than by the appended claims when given the range of equivalents to which my patent may be entitled.

I claim:

- 10 1. In the manufacture of electrolytic condensers and the like of the type embodying a container having an opening therein, an electrode disposed in the container, a soft rubber closure member for the container and a terminal for the electrode passing through said closure member, which includes the steps of placing the electrode within the container, positioning the closure member in the opening of the container with the terminal extending therethrough, forming two 15 openings through said member, inserting tubes through said openings, circulating an electrolyte within said container through said tubes and at the same time subjecting the condenser to an electrolytic aging process, thereafter withdrawing said electrolyte from the container and supplying another electrolyte to said container, withdrawing said tubes from said member, and subjecting said member to sufficient compressive force to 20 close said openings.
- 20 2. In the manufacture of electrolytic devices of the type having a container for electrolyte and an electrode disposed therein, the process which includes the steps of disposing the electrode within the container, connecting the container to a fluid circulating system, connecting the device 25 into an electric circuit and causing a current to flow therethrough to thereby subject the device to an electrolytic aging or filming operation, circulating one electrolyte within the container during at least part of the aging or film-forming operation, thereafter withdrawing said first electrolyte and supplying another electrolyte to said container, and finally disconnecting the container from the fluid circulating system and sealing the container without disturbing the assembled relationship of the parts or removing them 30 from the container.
